DEVICE FOR LOCATING SUNKEN VESSELS

Filed June 25, 1931

UNITED STATES PATENT OFFICE

LUDWIG H. ROETH, OF UNION CITY, NEW JERSEY

DEVICE FOR LOCATING SUNKEN VESSELS

Application filed June 25, 1931. Serial No. 546,720.

This invention relates to new and useful improvements in a ship locator.

The invention has for an object the construction of a ship locator which is characterized by the ability of giving the exact location of a sunken vessel to aid in its salvage.

As a still further object of this invention it is proposed to particularly provide a buoy in the fore and another in the aft part of the ship, which during the normal operation of the ship will be located upon the top deck and connected with extendable cables in a manner so that in the event of the ship sinking the buoys will float and thus locate it.

As a still further object of this invention it is proposed to provide a drum for the storing of the cable to be located in the bottom of the ship, a pipe extending from the bottom of the ship to the upper deck through which the cable extends where it is attached upon the bottom of the buoy.

Furthermore, another one of the objects of this invention is to arrange a funnel portion at the top of the pipe so that the buoys may rest thereon and shield the cable of the lower portions from possible damage due to water during the normal operation of the ship.

A still further object of this invention consists in the provision of means for allowing extension of the cables which support the buoys in a restricted way so that the buoys float directly over the ship instead of assuming positions to the side. It should be recognized that if the cables are extended too far the buoys can float to erroneous positions.

A still further object of this invention is the construction of a device of the class mentioned which is of simple, durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an illustration of a ship provided with buoys at the fore and aft constructed according to this invention. 55

Fig. 2 shows the ship in Fig. 1 in a sunken condition with the buoys indicating its sunken position.

Fig. 3 is a fragmentary enlarged sectional view of a portion of the ship showing in detail the construction and control mechanism of one of the buoys. 60

Fig. 4 is a fragmentary sectional view taken on the line 4—4 of Fig. 3.

Fig. 5 is a fragmentary sectional view 65 taken on the line 5—5 of Fig. 3, shown with the addition of schematic wiring.

Fig. 6 is a fragmentary plan view of Fig. 3.

Fig. 7 is a fragmentary sectional view 70 showing a modified form of conical member to support the buoy.

In Fig. 1, a ship 10 has been illustrated which is provided with a buoy 11 at its fore and a second buoy 12 at its aft. In Fig. 2 the ship 10 is shown sunken below the surface of the water and the buoys 11 and 12 on the surface indicating the location of the ship. 75 It should be noted that the cables 13 which extend from the buoys to the ship are in vertical condition so that the buoys are directly over the ship and do not float to one side. 80

Each of the buoys comprises a float 14, preferably made of cork, and having an inserted wood or hollow copper or brass member 15 provided with inscriptions such as 16 giving the name of the ship and other identification matter such as the port of registration and registration number. Furthermore, an inscription such as indicated by reference numeral 17 may be applied to indicate which buoy is to the fore of the ship and which is to the aft. 85 90

The inscription is also printed with clear 95 suitable type of lettering on top of the member 15.

The float 14 is supported within a frame structure 18 attached upon a conical member 19. This conical member is connected 100

upon the top of piping 20 which extends through the several decks 21 of the ship to the bottom. At the bottom, the pipe 20 extends into a housing 22 and terminates in a funnel portion 23 having an elongated opening 24. A cable 13 is attached upon the bottom of the float at the point where a portion of the float extends into the conical member 19 and extends through the full length of the pipe. 5 emerging through the opening 24. Within the housing 22, there is a pair of standards 26 which rotatively support a drum 27 upon which the cable 25 is wound. Any length of cable may be used depending upon the depth 10 of the water in which the ship navigates. 15 One of the ends of the drum is formed with teeth 28 engaged by a pawl 29 pivotally mounted and urged by a spring 30 into engagement with the teeth. This pawl serves as 20 a catch for holding the drum against rotation and consequently from giving off its cable.

A means is provided for releasing the catch allowing extension of the cable only 25 when the float 14 is dragged under the surface of the water. This means comprises a plurality of inclined passages 31 in the top of the float extending from the top face to the sides and located on all sides of the float. 30 These passages are positioned above the normal water line of the float. In each of the passages, spaced contacts 32 are mounted. These contacts are connected up in a circuit 33 so that the pairs of contacts are in series. 35 The circuit includes supply leads 34, an electromagnet 35, and the contacts 32. The wires forming the circuit 33 are loose as indicated by the coils 35 so that they may extend from the contacts 32 through the pipe 20 to the 40 electromagnet 35 which is located in the casting 22. The leads of the circuit should be of a length to correspond with the length of the cable 13 so that the float may be fully extended without causing breakage in the electrical 45 connections.

As the ship sinks, the floats 14 will be dragged under the water level so that the water fills the passages 31 and short circuits the contacts 32. Immediately the circuit 50 through the electromagnet 35 is closed causing it to lift the pawl 29 from the teeth 28. The drum can now rotate and give off cable until the ship reaches bottom and stops sinking. The float will then assume a position 55 in which the passages 31 are above the water and the circuit through the electromagnet will be broken so that the spring 30 prevents further giving off of cable. In this manner, just enough cable will be given off to locate 60 the floats directly over the ship. As the ship remains in its sunken position and the buoys are thrown around by the waves, one or more of the passages 31 may be temporarily filled 65 with water which will short circuit the particular contacts 32 within the passages but

which will not cause further giving off of cable since it is requisite that all of the passages 31 be simultaneously filled in that the contacts 32 are connected in series. The mere action of the waves cannot fill all of the passages at one time and therefore cable will not be given out unless the float is absolutely submerged due to further sinking of the ship, if this is possible. In such an event, more cable would be given off so that the floats assume positions at the surface of the water. 70 75

One of the crew of the sunken ship may remain upon the float or may be in a life boat or life raft attached to the float so as to claim possession of the sunken ship until he receives final instructions from proper authorities. 80

In Fig. 7 the conical member 19' is provided with a plurality of apertures 19^a to prevent the accumulation of dust, mud or any gummy substance. 85

It is to be understood that the funnel 19 and the entire device may be made of any suitable material and that the size and proportions may be changed to fit size of vessels. 90

While I have shown and described the preferred embodiment of my invention, it is to be understood that I do not limit myself to the precise construction herein disclosed and the right is reserved to all changes and modifications coming within the scope of the invention as defined in the appended claims. 95

Having thus described my invention, what I claim as new, and desire to secure by United States Letters Patent is:— 100

1. In a device for locating sunken vessels a float for location on the top deck of a ship a cable attached upon said float, a drum mounted on said ship and carrying turns of said cable, a catch for holding the drum against free rotations, and electrical means for releasing the catch allowing extension of the cable when the buoy is dragged under the water. 105

2. A ship locator, comprising a pair of buoys for location on the top deck of a ship at the fore and aft portions, each of said buoys comprising a float, means for supporting said float on the deck of the ship, a cable attached upon said float, a drum mounted on said ship and carrying turns of said cable, a catch for holding the drum against free rotations, and means for releasing the catch allowing extension of the cable when the buoy is dragged under the water, comprising spaced contacts within passages in said float and located above the normal water line of floating of the float, and a circuit including said spaced contacts in series and an electromagnet connected with said catch for its operation. 115 120 125

3. In a device for locating sunken vessels a float for location on the top deck of a ship, a cable attached upon said float, a drum mounted on said ship and carrying turns of 130

5 said cable, a catch for holding the drum against free rotations, and electrical means for releasing the catch allowing extension of the cable when the buoy is dragged under the water, comprising an electro-magnet connected with said catch for its operation, and means for energizing said electro-magnet upon submersion of said float.

10 4. In a device for locating sunken vessels a float for location on the top deck of a ship, a cable attached upon said float, a drum mounted on said ship and carrying turns of said cable, a catch for holding the drum against free rotations, and electrical means for releasing the catch allowing extension of the cable when the buoy is dragged under the water, comprising spaced contacts within 15 passages in said float and located above the normal water line of floating of the float, and means for operating said catch upon short-circuiting of the said contacts.

20 In testimony whereof I have affixed my signature.

LUDWIG H. ROETH.
